UNITED STATES PATENT OFFICE.

BENJAMIN C. BARTLEBAUGH, OF WHEELING, WEST VIRGINIA.

GAS HEATER.

1,403,730.

Specification of Letters Patent. Patented Jan. 17, 1922.

Application filed April 7, 1921. Serial No. 459,386.

To all whom it may concern:

Be it known that I, BENJAMIN C. BARTLEBAUGH, citizen of the United States, residing at Wheeling, in the county of Ohio and State of West Virginia, have invented certain new and useful Improvements in Gas Heaters; and I do declare the following to be a full, clear, and exact description of the invention, such as will enable others skilled in the art to which it appertains to make and use the same.

My invention relates to improvements in heaters and more particularly to those designed primarily for consuming gaseous fuel, one object of the invention being to provide a simple and inexpensive, yet highly efficient heater which will practically destroy the poisonous gases which usually escape into the room, novel provision being also made whereby there is absolutely no oxygen consumed from a great portion of the air which is heated.

In carrying out the above end, a further aim is to provide a construction in which a circulation of air takes place entirely around the burner, such air coming into contact with the flame of the burner, several times before any discharge of the air takes place, thereby insuring that the gases which are unburned as they discharge from the burner will be ultimately consumed rather than escape into the room.

A further object is to provide a gas heater which is designed for attachment directly to a gas line, requiring no other support, this being of particular advantage when there is little available floor space to accommodate a heater, under which circumstances, the gas line may be extended up the side of the wall and the heater placed at an elevated point, at which point it will not only be out of the way, but will be out of the reach of children.

With the foregoing in view, the invention resides in the novel construction and association of parts, hereinafter described and claimed, the descriptive matter being supplemented by the accompanying drawings.

Figure 1 is a side elevation of a gas heater constructed in accordance with my invention.

Figure 2 is a vertical sectional view as indicated by line 2—2 of Fig. 1.

Figure 3 is a horizontal sectional view as designated by line 3—3 of Fig. 2.

Figure 4 is a vertical transverse section as indicated by line 4—4 of Fig. 2.

Figure 5 is a top plan view with the top of the casing removed.

Figures 6 and 7 are respectively a top plan and a side elevation of a heater having a slightly different form of casing from that shown in the other views.

Figure 8 is a front elevation showing the appearance of the front to either form of construction.

In the drawings above briefly described, the numeral 1 designates a vertical casing whose back wall 2 is preferably of the curved formation disclosed in Figs. 1 to 5, although the formation illustrated at 2^a in Figs. 6 and 7 may well be employed if desired. The side walls 3 of the casing 1 are preferably turned inwardly toward each other at their front edges to provide flanges 4 to which upper and lower plates 5 and 6 are secured by bolts or the like 7, said plates being spaced apart sufficiently to provide the usual opening 8 in the front of the casing, which front is formed jointly by said plates and the flanges 4. The lower edge of the plate 5 and the upper edge of plate 6 are preferably beaded as indicated at 9, not only to reinforce the said plates, but to enhance the appearance of the device. The upper edge of the upper plate 5 is spaced downwardly from a top 10 with which the casing 1 is provided, whereby to form a heat escape 11 from the upper end of the casing, said top 10 being also provided with outlet openings which are designated by the numeral 12.

Positioned in the casing 1 and forming with the back wall 2, an air heating passage 13, is a vertical partition 14 whose side portions may well be bent forwardly as seen at 15 and secured against the inner sides of the casing side walls 3 and the flanges 4, the free edges of said portions 15 being preferably turned around the edges of the flanges 4 as indicated at 16. I have shown the upper edge of the partition 14 inclining forwardly and provided with a

- flange 17 which is secured by bolts or the like 18 to a crown plate 19, which plate is spaced downwardly from the top 10 and extends forwardly from the partition 14, the 5 front edge portion of said plate 19 being preferably bent downwardly as indicated at 20 and secured at 21 to the plate 5 in slightly spaced relation with the latter so as to provide an air escape passage 22.
- 10 Extending across the casing, in advance of the partition 14, is a vertical fire wall 23 whose upper and lower edges are disposed in spaced relation with the crown plate 19 and the lower end of the casing, respectively.
- 15 An appropriately elongated horizontal burner 24 is positioned in the casing in front of the fire wall 23 and is provided with perforations 25 which are so located as to direct jets of flame both forwardly and upwardly.
- 20 The burner 24 is connected by a short length of pipe 26 with an appropriate air mixer 27 which is adapted to be mounted directly on a gas line 28, so that this line serves as the sole support for the entire heater. The ends 25 of the burner 24 are provided with outwardly extending flanges 29 which inter-fit with inwardly turned flanges 30 on vertical plates 31 which are secured in the casing 1 at opposite sides of the latter. This arrangement of parts serves to effectively mount the casing 1 and attached parts on the burner 24, in such a manner that they may be removed from said burner simply by lifting them.
- 30 In operation, air enters the burner chamber through the opening 8 and the open bottom of the casing and comes in contact with the flame of the burner 24 so that this air is caused to circulate around the burner and the fire wall 23 in the manner indicated by the arrows. Any gases which may escape through the perforations 25 without being burned by their initial exposure to the flame, will be subsequently brought into engagement with such flame so that they will eventually be consumed instead of being discharged into the room. The circulation of the hot air and gases in the front portion of the casing effectively heats the partition 40 14 and the crown plate 19, so that air entering the lower end of the passage 13 and rising in the latter will be effectively heated before it is discharged through the openings 11 and 12. This air, it will be noted, is highly heated without coming in contact with the flame and having any of its oxygen consumed, this being greatly to the advantage of persons occupying the room in which the heater is located. The hot air 50 from the burner chamber eventually escapes, partly through the opening 8 and partly through the passage 22 and attention may here be directed to the fact that all air escaping through said passage, will first mix

with the heated air from the passage 13, 65 from which no oxygen has been removed.

Mounting the burner 24 directly upon the gas line is advantageous in a number of ways, but particularly when only a very little floor space is available. Under these 70 circumstances, the gas line 28 may be extended upwardly along the wall and the heater mounted at an elevated point so as to be entirely out of the way and to be out of the reach of children, preventing serious 75 burns which are now often inflicted by the gas heaters now in use. Whenever desired, the entire casing may be lifted from the burner.

Since excellent results may be obtained 80 from the heater as disclosed, these details are preferably followed, but I wish it understood that within the scope of the invention as claimed, numerous minor changes may be made.

I claim:

1. A heater of the class described comprising a casing having a top provided with heat outlets, a vertical partition in said casing forming with the back wall of said casing an air heating passage having an inlet at its lower end, a crown plate extending forwardly from the upper end of the partition in spaced relation with the top, a fire wall in said casing spaced forwardly from the partition and having its upper and lower ends spaced vertically from the crown plate and the lower end of the casing respectively, and a burner in said casing in front of said fire wall.

2. A heater of the class described comprising a casing having a top provided with heat outlets, a vertical partition in said casing forming with the back wall of said casing an air heating passage having an inlet at its lower end, a crown plate extending forwardly from the upper end of the partition in spaced relation with the top, and having its front end bent downwardly in spaced relation with the upper portion of the casing front, a fire wall in said casing spaced forwardly from said partition and having its upper and lower ends spaced vertically from said crown plate and the lower end of the casing respectively, and a burner in said casing in front of said fire wall.

3. A heater of the class described comprising a horizontally elongated burner having its ends disposed in vertical planes and provided with outstanding substantially vertical flanges, a heater casing containing said burner, and hook-like flanges on the vertical walls of said heater casing engaging the flanges of said burner to detachably mount said casing upon said burner, the latter being adapted to be supported by a rigid gas-line.

4. A heater of the class described comprising a horizontally elongated burner having

its ends disposed in vertical planes and provided with substantially vertical outstanding flanges, means for mounting said burner directly on a rigid gas-line, a heater casing containing said burner, and substantially vertical plates secured to the side walls of said heater casing and having hook-like

flanges engaging the flanges of said burner to detachably support the heater casing upon said burner.

In testimony whereof I have hereunto set my hand.

BENJAMIN C. BARTLEBAUGH.
